AUTOMATIC GAS SHUT-OFF VALVE

Filed March 8, 1928

Fig. 1. A cross-sectional view of the assembly. It features a central vertical shaft with a gear at the top. A piston (3) is positioned within a cylinder (2). Various components are labeled with numbers: 1, 9, 11, 14, 15, 2, 3, 5, 6, 7, 8, 10, 12, 13, 16, 17, 19, 21, 22, 23, 24, 25, 26, 28, 29, 30, 31, 32, 33, 35, 36, 37, 38, 40, 41, 43, 44, and 45.

Fig. 2. A cross-sectional view of the assembly, similar to Fig. 1 but with different internal configurations. Components are labeled with numbers: 1, 9, 11, 14, 15, 2, 3, 5, 6, 7, 8, 10, 12, 13, 16, 17, 19, 21, 22, 23, 24, 25, 26, 28, 29, 30, 31, 32, 33, 35, 36, 37, 38, 40, 41, 43, 44, and 45.

Fig. 4. A top-down view of the assembly, showing the arrangement of the shaft, gear, and piston. Components are labeled with numbers: 2, 3, 4, 5, 6, 7, 8, 10, 12, 13, 14, 15, 16, 17, 19, 21, 22, 23, 24, 25, 26, 28, 29, 30, 31, 32, 33, 34, 35, 36, 37, 38, 39, 40, 41, 42, 43, 44, and 45.

UNITED STATES PATENT OFFICE

LUTHER D. LOVEKIN, OF WYNNEWOOD, PENNSYLVANIA

AUTOMATIC GAS SHUT-OFF VALVE

Application filed March 8, 1928. Serial No. 259,979.

In the operation of hot water heaters and boilers utilizing gas as the heating medium, excessive temperatures are frequently attained which are apt to cause damage to the heating apparatus.

The general object of my invention is to prevent this difficulty by providing means of novel construction adapted to permit operation of a valve to cut off the gas supply in the event that a dangerously high temperature should be reached.

A further object of the invention is to provide novel means including a fusible disc which is adapted to yield to permit the closing of a valve to cut off the supply of gas to a burner or heating device in case the water in the boiler of a water heater or boiler of other character with which the said means may be associated should become heated to a temperature beyond the limit of safety for the particular boiler.

It also is an object of the invention to provide a device of the character indicated in which the fusible disc referred to is insulated from the gas which may flow through the valve, whereby the withdrawal of heat from said disc by the flow of gas through the valve body or casing is prevented and whereby also the temperature of said disc will be more nearly the same as that of the water in the boiler with which the said device may be associated. This will permit the valve to close the instant that a predetermined maximum temperature of the water in the boiler is attained.

A more specific object of the invention resides in constructing a mounting for the fusible disc, referred to above, which may be easily inserted into and removed from the valve mechanism of which it forms a part.

In order to better understand the advantages of my invention, reference may be had to the accompanying drawing, in which I have illustrated one embodiment thereof. However, it is to be understood that the invention is susceptible of embodiment in other forms of construction than that shown and that various changes may be made in the details of construction without departing from the invention as defined in the claims.

In the drawing:

Fig. 1 is a view in longitudinal section of a device embodying my invention attached to a boiler or hot water tank and showing the valve in its normally open position;

Fig. 2 is a similar view of the device showing the valve after it has been moved into closed position;

Fig. 3 is a transverse sectional view taken on the line 3—3 of Fig. 1; and

Fig. 4 is a view showing in longitudinal section a modified structure embodying the invention, certain parts of the structure shown in Figs. 1 and 2 being broken away and omitted.

The numeral 1 designates a valve body having internally screw-threaded openings 2, either one of which will constitute the inlet to the valve and the other the outlet, and with which the gas supply and delivery pipes (not shown) will be connected in the usual manner. The interior of the valve body is traversed by a partition 3 having a port 4 therethrough which is controlled by the valve 5, as will be later described. The valve 5 is held in alignment with the port 4 by means of an integral sleeve 6 having a sliding fit in the cap 7, accurately machined to receive the same and attached to the valve casing by suitable screw threads. The bottom of a recess 8 in the partition 3 constitutes a valve seat with which the valve 5 engages when it is free to move to its closed position. The spring 9 which is inserted between the valve 5 and the closed end of the cap 7 constantly urges the valve 5 to closed position.

A valve rod or stem 10, having an enlarged head 11, is secured to the valve 5 by means of the nut 12, as is clearly shown, and if desired, a pin 13 may be provided in the rod 10 to retain the nut 12 in place. Assemblage of the valve rod 10 and the valve 5 is facilitated by a screw driver slot 14, which is cut in the end of the enlargement 11 already referred to. The slot 14 may also be engaged by a suitable grinding tool to grind the valve 5 to its seat 8. The grinding tool (not shown) may be inserted into the cap 7 by removing the screw-threaded plug 15.

A hollow integral extension 16 is formed

on the valve body 1, as is clearly shown. The extension 16 is provided with screw threads which permit the valve to be attached as a unit to a hot water tank or boiler 17, and when so positioned the extension 16 will protrude into the tank or boiler 17, as shown in the drawings. A disc 18 is fit snugly into a recess 19 which is cut on the interior of the valve body or casing 1 where it joins with the extension 16 already referred to. The disc 18 normally is held in position by means of a spring 20 inserted between the disc and the valve 5 and surrounding the rod 10. The said disc constitutes a guide for the stem 10 projected therethrough and also acts as a partition between the valve passage and the interior of the extension 16, for a purpose which will later appear. The disc may be withdrawn from its recess 19 by the action of a pin 21 which is inserted through the rod 10 and which will engage with the disc when the rod is moved outwardly from the valve casing.

The rod 10 normally rests against a fusible disc 22 which will soften when heated to a selected predetermined temperature, which disc is mounted within a cartridge 23 and held upon a shoulder 24 therein over an opening 25 in said cartridge by means of a sleeve nut 26. The interior of the hollow extension 16 is suitably bored to receive the cartridge 23, and in order to permit quick withdrawal of the cartridge, a pin 27 (similar to the pin 21 described above) is inserted through the rod or stem 10 after the free end of the latter has been projected through an opening 28 in the sleeve nut 26. Shoulders 29 are formed at the end of slots 30 which are provided interiorly of the sleeve nut 26. The slots are longitudinally disposed on the interior of the sleeve nut and are placed diametrically opposite one another, as shown. The slots will permit the pin 27, already referred to, to be drawn into contact with the said shoulders, and it will be apparent that by means of this construction the cartridge 23 may be removed from the valve casing by withdrawing the valve and its stem after the cap 7 has first been removed. The cartridge 23 may be adjusted to different positions in the extension 16 by means of the rod 31 which engages its inner end. The rod 31 is provided with exterior screw threads which engage interior screw threads in the extension 16, as shown at 32, and adjustment of the rod 31 is effected by engaging a wrench with the squared end 33. This adjustment must be made before the valve is attached to the tank or boiler. The adjustment is preferably made permanent by soldering or otherwise securing the rod 31 against movement in the sleeve 16. The primary purpose in providing the adjusting means just described is to prevent the cartridge 23 from jamming in the

extension 16 with which it has slidable engagement.

In the operation of the present invention the valve will be attached to a hot water tank or boiler by being tightly screwed into an opening located at a point near the top of the tank where it will be subjected to the maximum temperature of the water. The gas supply and delivery pipes will be connected to the valve in the usual way. It will be understood that before installing the device the cartridge containing the fusible disc will be adjusted in the casing as previously described, and the valve will be held in its open position by means of the stem 10 contacting with the said disc. The tubular extension 16 protruding into the tank is heated by the water therein, and it follows that the heat will be conducted through the rod 31 and the wall of the casing extension to the cartridge 23. From the latter the heat will be transmitted to the fusible disc 22, and when the water in the boiler reaches a certain temperature, which will be predetermined by the employment of a disc fusible at a selected temperature, the disc will soften sufficiently to permit the spring 9 to suddenly force the rod 10 through the same and into the opening 25. The valve 5 will then assume a closed position, as shown in Fig. 2.

The softening of the disc 22 enables it to be punctured by the rod 10, which virtually cuts a slug therefrom, as is illustrated in Fig. 2. This indicates that the closing action of the valve is quick and positive and not of sufficient duration to permit "flareback" of the gas burner.

After the valve 5 has closed, as just described, the valve, together with the valve rod 10, the partition 18, and the cartridge 23, may be quickly withdrawn from the valve casing by unscrewing the cap 7. In practice it is found that if the punctured disc is permitted to remain in the cartridge it will melt and tend to solder the parts together. It is therefore desirable to withdraw the cartridge and its perforated disc from the casing in the manner above described as soon as the latter has been punctured. The punctured disc may then be replaced by a new or unpunctured disc and the device made ready for further use.

In Fig. 4 a modified form of device embodying the invention is shown, with parts broken away. The valve casing 34 has a tubular extension 35 formed integrally therewith and by means of which the valve is attached to a boiler or tank. The extension 35 is bored to receive a plurality of partitions 36 through which the rod 37 is guided. The rod 37 normally centers and bears upon the fusible disc 38 carried in the cartridge 39. The cartridge 39 is adapted to be adjusted in the same manner as the cartridge 23 of Fig. 1 by means of the screw-threaded plug 40. The

space between the cartridge and the adjoining interior portion of the extension 35 is exaggerated to emphasize the function of the screw-threaded plug 40 in preventing the cartridge from jamming in the said extension. The rod 37 is provided with a plurality of pins 41 which will engage respectively with the partitions 36 to effect their withdrawal. A pin 42 is also provided in order to withdraw the cartridge 39 from the extension 35. The valve rod 37 is provided with an enlarged head 43, normally engaged by the free end of a valve stem 44 which is separate from the said rod.

The operation of the modified construction of Fig. 4 is substantially the same as that of the construction shown in Figs. 1 and 2 except that a plurality of dead air spaces or pockets within the extension 35 further insure the fusible disc against the objectionable cooling effect thereon of the gas which flows through the valve. The construction of Fig. 4 also differs from that illustrated in Figs. 1 and 2 in that the extension 35 protrudes further into the tank or boiler than does the extension 16 and the plug 40 is relatively short as compared with the rod 31. The portion of the extension 35 within which the cartridge 39 is located projects into the water in the boiler so that said cartridge will be more directly affected by the heat of the water than in the construction of Figs. 1 and 2.

It will be noted that in both forms of construction the flow of gas through the valve casing or body will not appreciably alter the temperature of the disc 22 because of the presence of the dead air pockets or spaces in the construction shown in Figs. 1 and 2, and the similar spaces in the construction as illustrated in Fig. 4 wherein two of the pockets or spaces are provided. These air pockets or spaces constitute heat insulating means, and as a result of their presence the flow of cool gas through the passageway of the valve body or casing does not affect appreciably or in any substantial way the temperature of the fusible discs. In consequence the softening of the said discs to an extent to permit the puncturing thereof by either the rod 10 or the rod 37 takes place at all times when the water in the boiler or tank has attained a selected predetermined maximum temperature.

Having thus described my invention, what I claim and desire to secure by Letters Patent is:

1. An automatic gas shut-off valve, comprising a valve casing, a valve in said casing normally urged to closed position, a tubular extension formed on said valve casing, and a fusible disc adjustably mounted in said extension adapted to support said valve in open position.

2. An automatic gas shut-off valve, comprising a valve casing having a passageway therethrough, a valve in said casing for con-

trolling the flow through said passageway, means normally urging said valve to closed position, a tubular extension on said valve casing, means for adjustably mounting a fusible disc in said extension, a rod interposed between said valve and said fusible disc and operating to hold said valve in open position, and a partition between the valve passageway and the interior of the said extension.

3. An automatic gas shut-off valve, comprising a valve casing having a passageway therethrough, a valve adapted to control the flow of fluid through said passageway, a tubular extension on said valve casing, a fusible disc, means within said extension for adjustably supporting said fusible disc, a rod interposed between said valve and said disc and normally holding said valve in open position, means tending to move the valve to closed position, a partition between said valve passageway and the interior of the said extension, and means whereby the said partition and the said means for supporting the fusible disc may be withdrawn from the said extension by removal of said rod.

4. An automatic gas shut-off valve, comprising a valve casing having a passageway therethrough, a valve adapted to control the flow of fluid through said passageway, said valve being urged toward closed position, a tubular extension on said valve casing having temperature responsive means therein, a rod interposed between said valve and said temperature responsive means, said rod being normally supported by said temperature responsive means to hold said valve in open position, and means including a removable partition for providing a dead air space between the said passageway and said means.

5. An automatic gas shut-off valve, comprising a valve casing having a passageway therethrough, a valve in said casing adapted to control the flow of gas through said passageway and normally urged to closed position, a hollow extension projecting from said valve casing, temperature responsive means mounted in said extension adapted to support said valve in open position, and a removable partition provided in said casing which partition causes a dead air space to be formed for insulating said temperature responsive means from the flow of gas through said valve passageway.

6. An automatic gas shut-off valve, comprising a valve casing having a tubular extension formed thereon, a valve mounted in said casing, means provided in said extension having a fusible disk mounted therein, the said disk being engaged by one end of a rod the other end of which is connected to the said valve, the said disk normally operating to hold the said valve in open position, and means for removing said first named means from the said tubular extension by removal of said rod.

7. An automatic gas shut-off valve, comprising a valve casing having a tubular extension formed thereon, a valve mounted in said casing, means for mounting a fusible disk in said extension, a rod located in said casing one end of which contacts with the said disk and the other end of which is connected to the said valve, the said disk normally operating to hold the said valve in open position, means for adjusting said first named means in the said tubular extension, and means for removing the said first named means from the said tubular extension by removal of said rod.

10 8. An automatic gas shut-off valve, comprising a valve casing having a tubular extension formed thereon, a valve mounted in said casing, removable means provided in said extension for supporting a fusible disk therein with which disk contacts one end of a rod the other end of which is connected to the said valve, and the said disk normally operating to hold the said valve in open position, and means for connecting the said rod to the first named means.

15 9. An automatic gas shut-off valve, comprising a valve casing having a passageway therethrough, a valve adapted to control the flow of fluid through said passageway, a tubular extension formed on said valve casing, removable means located in said extension for supporting a fusible disk therein with which disk contacts one end of a rod the other end of which is connected to the said valve, a removable partition interposed between said passageway and the interior of the said extension, and means for connecting the said rod to the first named means and to the said partition.

20 10. An automatic gas shut-off valve, comprising a valve casing having a passageway therethrough, a valve adapted to control the flow of fluid through said passageway, a tubular extension formed on said valve casing, means located in said extension for supporting a fusible disk therein with which disk contacts one end of a rod the other end of which is connected to the said valve, a partition interposed between the said passageway and the interior of the said extension, and means for removing the said first named means and the said partition from the said valve casing by removal of said rod.

55 In testimony that I claim the foregoing as my invention, I have hereunto signed my name this 7th day of March, A. D. 1928.
